UNITED STATES PATENT OFFICE.

ABRAHAM ALBERT, OF SAN FRANCISCO, CALIFORNIA, ASSIGNOR, BY MESNE ASSIGNMENTS, TO MONARCH MANUFACTURING AND SUPPLY COMPANY, A CORPORATION.

ELECTRIC WATER-HEATER.

986,037.

Specification of Letters Patent. Patented Mar. 7, 1911.

Application filed May 21, 1910. Serial No. 562,626.

To all whom it may concern:

Be it known that I, ABRAHAM ALBERT, a citizen of the United States, residing in the city and county of San Francisco and State 5 of California, have invented certain new and useful Improvements in Electric Water-Heaters, of which the following is a specification.

The hereinafter described invention relates to an improved apparatus for the heating of water from a source of electrical supply, for use in homes, hotels, traveling conveyances, such as railway cars and boats; the object being the production of a simple, 15 compact, and inexpensive heater which may be conveniently carried by the person and easily applied to an electric fixture for securing electric power or current.

The construction of the heating appliance 20 is such that the electrical circuit is not completed until the same is partially or wholly submerged in the water to be heated, so that while the heater is out of the water and the current turned on the same may be freely 25 handled without fear of a shock to the user thereof, and, as the electric circuit is an open one at such time, without danger of the heater causing a fire, by being placed on the floor or other places while the electric current 30 rent is turned on.

To comprehend the invention reference should be had to the accompanying sheet of drawings, wherein—

Figure 1 is a perspective view of the 35 heater applied to an ordinary electric fixture. Fig. 2 is a longitudinal sectional view of the heater. Fig. 3 is a detail view of the inner member of the heater with one of the wires connected thereto. Fig. 4 is a cross 40 sectional plan view taken on line $a-a$ Fig. 1 of the drawings, said view disclosing the relative arrangement of the inner and outer members of the heater.

In the drawings, the numeral 1 is used to 45 designate the outer electrode of the heater and 2 the inner electrode thereof, which electrodes are constructed of any suitable metal and preferably of tubular form. The electrode 2 is of less diameter than the electrode 1, so that when the same is fitted within the said electrode 1 an annular space 3 exists between the electrodes.

The lower end of the electrode 1 is closed 50 by a cap or end piece 4 formed of insulating material and within a socket or de-

pressed seat 5 in said cap is fitted and held the lower end of the inner electrode 2. The cap 4 is provided with a central opening 6, which communicates with the interior of the electrode 2, when the same is fitted thereto. Within the upper end of the electrode 1 is fitted a handle 7, formed of insulating material, the reduced projecting boss 7' thereof fitting within the upper end of the electrode 2 and serving, in connection with the cap 4 65 to maintain the said electrode 2 in position with respect to the electrode 1.

Through a central bore in the handle 7, the current supply wires 8 and 8' are extended, the wire 8 passing through a laterally 70 disposed branch passage-way 9 in the handle and being thus held separated from its companion wire 8', which said companion wire is united to the electrode 2 at any suitable point, preferably adjacent the 75 upper end thereof. The wire 8 is connected to the electrode 1, adjacent its upper end, the terminal ends of the wire 8 and 8', which wires are inclosed within the usual insulated covering, being separated from 80 each other by the insulated handle 7.

To prevent the separation of the parts after being assembled, the electrode 1 is attached to the insulated handle 7 and to the end cap 4 by means of the securing pins 85 9', which extend through the ends of the tubular electrode 1 into the said handle 7 and cap 4. The terminal end of the wires 8 and 8' are preferably united respectively to the electrodes 1 and 2 by being soldered 90 thereto, although the manner of connecting these parts is immaterial, just so long as the wire of one electrode does not make contact with the opposing electrode.

To prevent the possibility of a short circuiting, a section of the upper end portion of the electrode 2 is removed to provide a clearance 10, and the handle 7 is so positioned relative to this clearance space as to place the exit of the passage-way 9 for the 95 wire 8 directly in line therewith, thus removing the same for a considerable distance from the electrode 2.

The outer shell or tubular electrode 1 is provided with a series of circumferentially 100 disposed perforations 12, and in the inner tubular electrode 2 a series of perforations or water circulating openings 12' are provided, so that when the electrical heater is wholly or partially immersed in the water 110

to be heated, the same will circulate freely through the wall of the electrodes 1 and 2, and by so doing come in contact with the exterior and interior wall surfaces thereof.

5 The supply or current wires 8 and 8' are connected at their outer ends to the contacts of an ordinary lamp plug 13, which fits within the socket 13' of the electrical fixture 14, the wires 8 and 8' being of such length 10 as to permit of a considerable range of movement for the electrical heater.

The moment the improved heater is placed in the vessel containing the water to be heated, the electric current having been previously turned on, the water enters the annular space 3 through the water spaces, openings or perforations 12 in the electrode 1, and into the tubular electrode 2 through the bore 6 of the end cap 4 and passes from the 20 interior of said electrode through the outlet openings or perforations 12' into the annular space 3, the water connection between the electrodes completing the electrical circuit, causing the current to flow through the 25 electrodes. The electric circuit being thus closed, the electrodes are quickly heated and the water almost instantaneously raised to boiling point. The moment the heater is removed from within the body of water the 30 electrical circuit is destroyed and the heater may be freely handled without shock to the operator, the electrodes quickly cooling off on the destruction of the circuit. Thus the heater is only in action on being placed in 35 the water to be heated, for at such other times the circuit is an open one.

While the communication between the annular space 3 and the body of water to be heated is established by means of perforations through the electrode 1 and from the interior of the electrode 2 by the perforations in the wall thereof, it is obvious that any form of passage-ways for the circulation of the water may be employed, and, if 45 so desired, the perforations of the electrode 2 may be dispensed with; the only essential being that an established water connection

be made between the electrodes. However, the construction illustrated is preferred, inasmuch as the water is exposed to a greater 50 heating surface and the heating of the water more quickly accomplished than otherwise would be the case.

While the electrodes are illustrated as tubular and of cylindrical form, it is obvious 55 that solid electrodes may be employed, and that the shape thereof may be varied as desired.

Having thus described the invention what is claimed as new and desired to be protected 60 by Letters Patent is—

1. An electrical water heater, the same comprising an insulated handle provided with passage-ways for the current wires, an outer cylindrical perforated electrode secured thereto, an inner cylindrical perforated electrode fitted within the outer electrode and secured to said handle to leave an annular water circulating space between the electrodes, an insulated connection between 70 the lower ends of the said electrodes for holding the same spaced at such portion, current supply wires extended through the insulated handle and connected one to each electrode, and means for connecting the said 75 wires to a source of electrical supply.

2. An electrical heater for the described purpose, the same comprising an insulated handle provided with passage-ways for current supply wires, a perforated outer electrode secured thereto, an inner electrode fitted to said handle to leave a water circulating passage-way between the electrodes, an insulated cap separating the electrodes at the lower ends thereof, and current wire extended through the insulated handle and connected to the respective electrodes. 85

In testimony whereof I have signed my name to this specification in the presence of two subscribing witnesses.

ABRAHAM ALBERT.
